UNITED STATES PATENT OFFICE.

BURNHAM C. STICKNEY, OF ELIZABETH, NEW JERSEY, ASSIGNOR TO UNDERWOOD TYPEWRITER COMPANY, OF NEW YORK, N. Y., A CORPORATION OF DELAWARE.

TYPEWRITING-MACHINE.

1,381,895.

Specification of Letters Patent. Patented June 14, 1921.

Application filed February 18, 1918. Serial No. 217,873.

To all whom it may concern:

Be it known that I, BURNHAM C. STICKNEY, a citizen of the United States, residing in Elizabeth, in the county of Union and 5 State of New Jersey, have invented certain new and useful Improvements in Typewriting-Machines, of which the following is a specification.

This invention relates to the class of devices disclosed in my application No. 212,215, filed January 17, 1918, in which the capacity of the column-stop-setting-mechanism disclosed in the McLaughlin Patent 10 No. 941,166, dated November 23, 1909, is increased by the expedient of adapting a plurality of spurs on a plurality of shafts to set the various column-stops; whereby it has been possible to secure at least as many different settings as there are different working 15 positions of the spur shafts operated separately; additional selections being practicable by using all of the spur shafts at the same time.

In the mechanism illustrated in said application and said patent, the column-stops are formed upon the front ends of blades or carriers which extent rearwardly in suitable guides, whereby considerable space is occupied at the rear of the typewriter carriage. In some machines, it is desired to occupy a large part of such space with other mechanism, as, for example, the adding mechanism of the well-known Underwood-Hanson combined typewriting and 20 adding machine. One of the main objects of the present invention is to secure the advantages of the device covered in said application, and at the same time keep the stop-mechanism from projecting behind the 25 back of the machine, as ordinarily built, thus avoiding such difficulties as the one above mentioned.

To this end the column-stop blades or carriers are mounted above the carriage, advantageously vertically, so that the column-stop proper is at the bottom end of the carrier. The column-stops normally stand too high to be reached by any of the denominational or counter-stops, which in the usual 30 Underwood typewriter, are arranged below the column-stops and adapted to be projected to be effective; each column-stop is set-table downwardly so as to be able to strike any projected denominational stop. Each 35 stop may be set by one or more suitable shafts

carrying stop-setting spurs. The entire mechanism is arranged very compactly and does not extend to an objectionable extent in rear of the typewriter carriage, and therefore, need not interfere with the adding 60 mechanism or other devices which it may be desired to place at the rear part of the machine, nor will it interfere with using machines embodying the present improvements in certain kinds of collapsible desks. Moreover, certain standard covers, which fit the 65 back of the ordinary typewriting machine rather closely, will also fit such machines.

Other features and advantages will hereinafter appear.

In the accompanying drawings,

Figure 1 is a rear elevation of an Underwood typewriting machine provided with the present improvements.

Fig. 2 is a side elevation upon a larger 7 scale, to show the arrangement of the column-stops and the stop-setting shafts.

Fig. 3 is a sectional, side elevation, taken about centrally of the typewriting machine.

As usual in the Underwood machine, the 80 decimal-tabulating keys 10 operate levers 11 to thrust up rods 12 having decimal stops 13 at their upper ends, and these rods have lugs 14 for operating a universal bar 15, which, by means of the usual connections, lifts a 85 rack 16 provided upon the typewriter carriage 17 free of the pinion 18 which controls the rack 16, so that the carriage 17 may run along until arrested at a point determined by the lifted decimal stop 13. Said pinion 90 18 is connected to an escapement wheel 19, whose motion is controlled by means of dogs 20 operated by a universal bar 21, the latter being engaged by the heels 22 of the type-bars 23 as they are manipulated by the keys 95 24, to print upon the paper carried upon the platen 25 mounted on said carriage. For simplicity, the machine shown herein is provided with a shiftless platen. Those who are skilled in the art will readily see how 100 my invention is to be applied to shiftable platen machines.

The column-stops 26 normally stand at too high an elevation to be reached by the decimal stops 13, and in order to enable any 105 column-stop 26 to be set down to working position, these column-stops are mounted upon blades or carriers 27 which stand vertically, the column-stops being formed upon the lower ends thereof.

Upon the front edge of each blade or carrier 27 are provided two or more lugs 28, which are engageable by setting spurs 29, carried upon upper and lower shafts 30 and 31. These spurs 29 are provided upon collars 32 which can be secured at different selected points at letter-space or other intervals along each shaft 30 and 31, and each collar 32 may have one, two, three or four spurs 29 thereon, in order to meet the various requirements. One shaft 30 or 31 may have an arrangement of collars 32 and spurs 29 capable of making four selections or settings of the column-stops; the same may be true of the other shaft, so that eight different settings of the column-stops are possible. Each shaft, however, may have more than four working positions, thus increasing the selecting capacity of the stop-selecting mechanism; and it will be understood that there may be more than two spur shafts, and a corresponding number of lugs may be added to each column-stop carrier.

Each spur shaft has its spurs so located thereon that its spurs may be either effective or ineffective,—the shaft being adapted to rest at an ineffective position intermediate each two effective positions.

When either spur shaft is operated, the other spur shaft may be in a neutral position, whereby the stops may be moved independently thereof by the other shaft. Hence, each shaft is capable of four working positions and four neutral positions; the shafts being held in any of these positions by means of spring detents 33 and notched wheels 34 with which they engage; the teeth 35 of the wheels being preferably ratchet teeth adapted to prevent backward rotation of the shafts under the torque produced by the springs 43.

Each shaft 30, 31 may be provided with a thumb wheel 36 for turning the same, and upon said wheel may be arranged a scale 45 in the form of numbers, each position of the stops having a number of its own, the scale being, therefore, partly upon one thumb wheel 36 and partly upon the other; and suitable pointers or indexes 37 may be provided for said scales, said pointers being mounted on the brackets 37^a which are fast on the typewriter carriage and form the journals for the shafts 30, 31. The blades or carriers 27 may be guided in upper and lower racks 38, 39, the upper rack preferably having notches 40 upon its front and rear edges, to receive the forks 41 with which the blade is formed, and being carried upon brackets 42 screwed upon the end of the lower rack 39; returning springs 43 for the column-stops being arranged within the forks and anchored in the upper rack bar 38. The lower rack 39 may consist of notches 44 cut in the front of a bar 45, 65 which is supported upon brackets 46 car-

ried upon the ends of the carriage; and each carrier may be provided with a stop 47 for limiting its return movement.

Each spur 29 may be capable of holding each column-stop 26 down in working position, as seen at the upper part of Fig. 3 or the lower part of Fig. 2; and the spring detents 33, by coöperation with the abrupt faces of the ratchet wheel teeth 35, may lock the spur shafts against being turned backwardly by the tension of said springs 43, which are provided for returning the column-stops.

In order to avoid any possibility of confusion on the part of the typist in moving the handles 36, one handle may be placed at the right-hand end of the carriage, and the other at the left-hand end.

Variations may be resorted to within the scope of the invention, and portions of the improvements may be used without others.

Having thus described my invention, I claim:

1. In a typewriter, in combination, a carriage, a support therefor, a tabulating mechanism comprising a tabulator-stop mounted at the rear of said support and an attachment mounted on said carriage so as not to extend to the rear of the typewriter frame, said attachment comprising a set of column-stops so mounted as to be movable with the carriage over said tabulator-stop, each of said column-stops being slidable vertically from a normal ineffective position to a set position in which it may coöperate with 95 said tabulator-stop to arrest said carriage, and a selective stop-setting device capable of effecting a setting of a plurality of stops of said set at a single operation, and also capable of effecting a plurality of different settings of stops of said set at a plurality of successive operations.

2. In a typewriter, in combination, a carriage, a support therefor, a tabulating mechanism comprising a tabulator-stop 110 mounted at the rear of said support, a set of column-stops mounted on the rear of said carriage so as to be movable therewith over said tabulator-stop, each of said column-stops being slidable vertically from a normal ineffective position to a set position in which it may coöperate with said tabulator-stop to arrest said carriage, and a plurality of selective stop-setting devices, each capable of effecting a setting of a plurality of stops of 115 said set at a single operation, and also capable of effecting a plurality of different settings of stops of said set at a plurality of successive operations, and each being capable of effecting settings differing from the settings which may be effected by another.

3. In a typewriter, in combination, a carriage, a support therefor, a tabulating mechanism comprising a tabulator-stop mounted at the rear of said support, a set of 130

- column-stops mounted on the rear of said carriage so as to be movable therewith over said tabulator-stop, each of said column-stops being slidable vertically from a normal successive operations, said setting device being mounted on said carriage along said column-stops and between the same and the 35 platen.
5. In a typewriter, in combination, a platen and its carriage, a support for said carriage, a tabulating mechanism comprising a tabulator-stop mounted at the rear of said 40 support, a set of column-stops mounted on the rear of said carriage so as to be movable therewith over said tabulator-stop, each of said column-stops being movable from a normal ineffective position to a set position 45 in which it may coöperate with said tabulator-stop to arrest said carriage, and a plurality of selective stop-setting devices, each capable of effecting a setting of a plurality of stops of said set at a single operation, and also capable of effecting a plurality of different settings of stops of said set at a plurality of successive operations, said setting devices being capable of being used conjointly to effect 50 settings differing from those which may be effected by any one alone.
4. In a typewriter, in combination, a platen and its carriage, a support for said carriage, a tabulating mechanism comprising 20 a tabulator-stop mounted at the rear of said support, a set of column-stops mounted on the rear of said carriage so as to be movable therewith over said tabulator-stop, each of said column-stops being slidable vertically from a normal ineffective position to a set position 55 in which it may coöperate with said tabulator-stop to arrest said carriage, and a selective stop-setting device capable of effecting a setting of a plurality of stops of said set at a single operation, and also capable of effecting a plurality of different settings of stops of said set at a plurality of another, said setting devices being mounted on said carriage along said column-stops, one above another, and between the same and the platen.
